UNITED STATES PATENT OFFICE.

WILLARD F. RICHARDS, OF BUFFALO, NEW YORK.

DESIGN FOR AN ELECTRODE OR BATTERY-PLATE.

SPECIFICATION forming part of Design No. 32,161, dated January 30, 1900.

Application filed December 13, 1897. Serial No. 661,751. Term of patent 14 years.

To all whom it may concern:

Be it known that I, WILLARD F. RICHARDS, a citizen of the United States, residing at Buffalo, in the county of Erie and State of New York, have invented and produced a new and original Design for Electrodes or Battery-Plates, of which the following is a specification, reference being had to the accompanying drawing, forming a part thereof.

10 This design relates to the configuration of the lead electrodes or plates of secondary or storage batteries.

The accompanying drawing is a perspective view of an electrode or battery-plate embodying my design.

15 The leading feature of my design consists of a flat plate having a series of parallel dove-

tail grooves or channels on each exposed flat side thereof.

A is the flat-sided battery-plate, and b represents the narrow dovetail grooves, which are arranged parallel with each other and extend continuously from edge to edge of the plate.

What I claim is—

25 The design for an electrode or battery-plate, substantially as herein shown and described.

Witness my hand this 6th day of December, 1897.

WILLARD F. RICHARDS.

Witnesses:

CARL F. GEYER,
JNO. J. BONNER.
